UNITED STATES PATENT OFFICE

WILLIAM J. MALONEY, OF ANSONIA, CONNECTICUT, ASSIGNOR OF ONE-TENTH TO
WILLIAM J. MALONEY, JR., OF ANSONIA, CONNECTICUT

CONCEALED THUMB TACK

Application filed March 27, 1931. Serial No. 525,663.

This invention relates to new and useful improvements in securing or fastening means of the type including a pointed part or element adapted to penetrate into a supporting 5 part or surface as for example, a post, wall or the like.

An object of the invention is to provide a means as stated and including a housing in which the pointed or penetrating element or 10 part of the securing means is normally concealed and from which it is adapted to be readily projected.

Another object is to provide a securing means including a housing open at opposite 15 ends and a pointed or penetrating element normally disposed within the housing and having a head or operating portion projecting through the one end of the housing and adapted to be manipulated to project the 20 pointed element at the opposite end of the housing, the head being colored or ornamented, as by a fraternity insignia, or plain as desired.

A further object is to provide a securing 25 means including a housing and a pointed or penetrating element, a spring means being provided for normally holding the pointed element within the housing but to permit the element to be projected from the housing for 30 operation.

An additional object is to provide a fastening or securing means as stated and which may be secured to a hat or other article of apparel to be used for hanging or securing 35 the same to a wall or the like.

Other objects and advantages will become apparent from a consideration of the following detailed description taken in connection with the accompanying drawings wherein the invention is illustrated. However, it will be understood that the invention is not limited to the details disclosed but includes such modifications and variations as fall 40 within the scope of the appended claims to which claims reference is to be had for a definition of the invention.

In the drawings:

Fig. 1 is a view showing the application of 50 the invention to a hat, portions of the hat being broken away;

Fig. 2 is a vertical sectional view on an enlarged scale showing the inner construction of the improved securing means;

Fig. 3 is a transverse sectional view on the line 3—3 of Fig. 2; and

Fig. 4 is a view partly in section and partly in side elevation showing a slightly modified construction of securing means.

Referring in detail to the drawings, and first particularly to Fig. 1, the invention or 60 the securing means of the invention is shown as applied to a hat 5 including a crown 6 and a brim 7. Secured or attached to the brim 7 and to the crown 6 are a pair of attaching or 65 securing means 8 the construction of which is fully shown in the other view. The manner of mounting or attaching the securing means 8 to the hat will later be described in detail. However, the function of this means is to secure the hat to a wall or the like as 70 suggested at 9, the securing means including a pin or pointed element adapted to be pressed into the wall.

The securing means 8, as clearly shown by 75 Figs. 2 and 3, includes a substantially cylindrical casing or housing 10 having an opening through its upper or end wall 11. The end wall 12 opposite the wall 11 is provided with a central opening 13 and this wall includes an extension or nipple 14 forming an 80 open neck or throat 15 adapted to have its free end turned over as at 16 whereby to clamp portions of the hat brim 7 between said turned over portions 16 and the wall 12 to secure the housing to the hat brim. Obviously, the 85 housing may be similarly secured to the crown or the hat or to some other article of clothing.

Arranged within the housing 10 is a pin or pointed element or part 17 having its upper 90 or blunt end portion knurled or roughened as at 18. Secured on the blunt portion of the pin 17 and inwardly of the blunt end thereof is a button-like part or member 19 of a diameter to snugly fit through the opening in the wall 11 of the housing and carrying a flange 20 adapted to engage the inner surface 95 of the wall 11 to prevent movement of the button out of the housing. This button or member 19 may be of wood or bakelite or 100

other material colored and ornamented if desired.

Secured on the extreme end of the blunt portion of the pin 17 and enclosing said portion as clearly shown in Fig. 2 is a relatively small button or block 21 which may as shown be of a diameter less than the diameter of the button 19. The button or block 21 may be ornamented if desired and may be made of wood, bakelite or other material and may be colored to contrast with the color of the button 19. Also, if desired, the outer end of the button 21 may have a fraternity emblem or other insignia formed or secured thereon.

15 The flanged portion 20 or the flange 20 of the button 19 is of such diameter that it is reciprocatable within the housing 10 and will assist in maintaining the button against rocking movement during reciprocation of the 20 button. Further, the fit of the button 19 through the opening in the wall 11 of the housing is such that the button will not rock. The location of the button 19 is such as to hold the pointed element or pin 17 in alignment 25 with the opening 13 and throat 15 through the bottom or end wall 12 of the casing.

Within the housing or casing 10 and surrounding the pin 17 is a light coil spring 22. At one end the spring 22 bears against the inner surface of the button 11 and at its opposite end the spring bears against the inner surface of the wall 12 of the housing. Therefore, it will be seen that the action of the 30 spring 22 will be such as to maintain the pin 17 in its retracted position or within the housing. The pin may be projected from the housing by pressing on the upper or outer button 21 whereby to compress the spring and, of course, the pin may be projected from 35 the housing and into a wall or the like whereby to secure the entire device and a hat or other garment to which it may be attached, to the wall or other support.

40 Of course, after the pin has been projected, as for example, to secure a hat to a wall or other support, and has then been withdrawn from the support, the spring 22 will act to retract the pin or to draw the pin into the housing as stated above, but a light spring is employed at 22 the spring being only of the strength required to move the pin into the housing and not being of sufficient strength to draw the pin out of a wall or other support.

45 I have provided means to prevent the accidental or casual operation of the button 21 in such a manner as to project the pin 17. This means as herein disclosed comprises a lever member 23 pivoted to the lower wall 12 of the housing intermediate the ends of the lever as at 24. The lever includes an enlarged portion or head 25 and an operating end or hand portion 26 projecting through a slot 27 in the housing. It will be clear that the lever 23 50 may be shifted from the operative full line

position of Fig. 3 to the inoperative position shown by the dotted lines in that figure. Further, it will be understood that when the lever 23 is in the position shown in full lines in Figs. 2 and 3 its enlarged portion or head 25 is disposed centrally of the wall 12 and over the opening 13 and throat 15 in a position to prevent downward movement of the pin 17. Therefore, the pin may not be casually projected from the casing and if it is 55 desired to project the pin it will be first necessary to move the lever 23 about its pivot 24 and to a position toward one side of the housing.

60 In Fig. 4 a slightly modified form of the invention is shown, the securing or fastening means as shown in this figure being particularly adapted for the hanging of pictures or the like. In this figure the nipple or extension 14 does not have its free end portion turned over and is externally screw threaded as at 28. Threaded on to the nipple is an externally tapered or inclined ring 29, the ring being preferably fully threaded on to the nipple whereby the enlarged end surface of 65 the ring abuts the outer surface of the end wall 12 of the housing 10.

70 The securing means as shown in Fig. 4 also includes the safety lever 23 and the coil spring 22 as in the other forms of the invention and the pin 17 is also adapted to be projected by pressure applied to the outer end of the button 21. When the device is applied to a wall or the like, as suggested by the dotted lines 30 in Fig. 4, the pin 17 will, of course, 75 be projected to its dotted line position of Fig. 4 and the frictional engagement of the pin with the material into which it has penetrated will support the housing and prevent retraction of the pin by the spring 22. Since the 80 outer surface of the ring 29 is tapered or inclined a picture wire or other supporting means 31 will naturally assume a position 85 against the wall 30 as shown in Fig. 4.

85 In either form of the invention, the housing 10 may be provided with one or more vent openings 32 and it will be seen that when the device is applied to a crown of a hat as shown in Fig. 1 there will be an air passage from the interior of the hat. It will further be understood that the invention may be used in 90 connections other than those suggested herein and by the drawings, and it will also be apparent that the ring 29 of Fig. 4 might be used to clamp some article or material against 95 the outer surface of the wall 12 of the housing whereby to attach the securing means to the article or material.

100 Having thus set forth the nature of my invention, what I claim is:

105 1. In a securing means, a housing open at one end, a pointed element, means serving to normally retain said element within the housing, means adapted to be operated to project the element through the open end of 110

- the housing and into a support to mount the housing on the support, and means for securing the housing to an article to be supported.
- 5 2. In a securing means, a housing open at one end, a pointed element, means serving to normally retain said element in an inoperative position within the housing, means adapted to be operated to project the element through the open end of the housing, and shiftable means adapted to be disposed in the path of the pointed element to prevent operation thereof and adapted to be moved out of the path of the pointed element to permit operation thereof.
- 10 3. In a securing means, a housing open at one end, a pointed penetrating element, means serving to normally retain said element within the housing, means adapted to be operated to project the element through the open end of the housing and into a support to attach the housing to the support, and said housing at said open end including means for clamping an article to be supported
- 15 4. In a securing means, a housing open at one end, a pointed penetrating element, means serving to normally retain said element within the housing, means adapted to be operated to project the element through the open end of the housing and into a support to attach the housing to the support, said housing having a tubular extension thereon providing a restricted passage communicating with the opening in the end wall of the housing and through which the pointed element may be projected, and said extension adapted to be passed through and turned over to clamp an article to be supported
- 20 5. In a securing means, a housing open at one end, a pointed element, means serving to normally retain said element within the housing, means adapted to be operated to project the element through the open end of the housing and into a support to attach the housing to the support, said housing having a tubular extension thereon providing a restricted passage communicating with the opening in the end wall of the housing and through which the pointed element may be projected, and said extension adapted to be passed through and turned over to clamp an article to be supported
- 25 6. In a securing means, a housing open at one end, a pointed element, said element having a head projecting through one of the open ends of the housing, a coil spring within the housing and surrounding the element and at one end bearing against said head and at its other end against a wall of the housing whereby to normally retain the element within the housing, said head having an enlargement to limit the extent of movement of the head outwardly of the housing,

and said head adapted to be pressed to compress the coil spring and project the pointed element through the opposite open end of the housing and into a support to attach the housing to the support.

7. In a securing means, a housing open at one end, a pointed element, means serving to normally retain the pointed element within the housing, means for securing the housing to an article to be supported and with the open end of the housing disposed at one side of the article, means adapted to be operated to project the pointed element through the open end of the housing and into a support to mount the housing and article on the support, and said housing having openings therein at the opposite side of the article and communicating with the open end of the housing to provide for ventilation.

In testimony whereof I affix my signature.

WILLIAM J. MALONEY.
